(57) CLAIM

The ornamental design for a imitation engraved bean bag, as shown and described.

DESCRIPTION

FIG. 1 is a perspective view of a imitation engraved bean bag showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a perspective view thereof shown in an environment showing the use of the pedal in conjunction with the pedal. The broken lines depict portions of the imitation engraved bean bag and form no part of the claimed design.
